(57) **CLAIM**

The ornamental design for a weigh scale toy, as shown and described.

DESCRIPTION

FIG. 1 is a first perspective view of our weigh scale toy, shown in combination with unclaimed buckets.

FIG. 2 is a second perspective view thereof.

FIG. 3 is a front view thereof.

FIG. 4 is a back view thereof.

FIG. 5 is a right side view thereof.

FIG. 6 is a left side view thereof.

FIG. 7 is a top view thereof; and,

FIG. 8 is a bottom view thereof.

In some implementations, sliding sleeves are provided on the arms of the weigh scale toy, as illustrated by dashed line in FIGS. 1-7.

The broken lines shown are included for the purpose of illustrating portions of the weigh scale toy that form no part of the claimed design.
